CLAIM

The ornamental design for the arm positioning aid for golf swing training, as shown and described.

DESCRIPTION

FIG. 1 is a top isometric view of an arm positioning aid for golf swing training showing our new design;

FIG. 2 is a top plan view of the arm positioning aid for golf swing training of FIG. 1;

FIG. 3 is a bottom plan view of the arm positioning aid for golf swing training of FIG. 1;

FIG. 4 is a right side elevation view of the arm positioning aid for golf swing training of FIG. 1;

FIG. 5 is a left side elevation view of the arm positioning aid for golf swing training of FIG. 1;

FIG. 6 is a front elevation view of the arm positioning aid for golf swing training of FIG. 1;

FIG. 7 is a rear elevation view of the arm positioning aid for golf swing training of FIG. 1; and,

FIG. 8 is a cross-sectional view of the arm positioning aid for golf swing training of FIG. 1, taken substantially along lines 8-8 of FIG. 3.

The features shown in broken lines in the drawing depict portions of the design that form no part of the claimed design.
